UNITED STATES PATENT OFFICE.

WILLARD R. MILES, OF DENVER, COLORADO.

REFRIGERATOR-CAR DRAIN.

1,184,554.

Specification of Letters Patent. Patented May 23, 1916.

Application filed September 11, 1915. Serial No. 50,270.

To all whom it may concern:

Be it known that I, WILLARD R. MILES, a citizen of the United States, residing at Denver, in the county of Denver and State of Colorado, have invented certain new and useful Improvements in Refrigerator-Car Drains; and I do hereby declare the following to be a full, clear, and exact description of the invention, such as will enable others skilled in the art to which it appertains to make and use the same.

The invention relates to improvements in refrigerator car drains.

Heretofore considerable difficulty has been experienced with the refrigerator car drains in common and much damage and loss to railroads have been incurred through the flooding of cars due to stoppage of the drain pipe which in the ordinary construction in present use has an interiorly arranged trap which cannot be seen and inspected and which has to be cleaned by a rod. Furthermore with the drain in ordinary use it is customary in cold weather to plug up the drain pipe with waste or straw which is frequently overlooked when the car is iced thereby causing a flooded car that is not discovered until the car reaches its destination.

The object of the present invention is to obviate the aforesaid objections and improve the construction of refrigerator car drains and to provide a simple, practical and comparatively inexpensive drain having an exteriorly arranged trap adapted to be readily inspected and cleaned if necessary.

A further object of the invention is to provide a refrigerator car drain adapted through the motion of a refrigerator car to automatically throw out any accumulation of cinders or the like so that cleaning of the drain will be rendered unnecessary.

Another object of the invention is to provide a refrigerator car drain adapted to vary the size of the outlet or discharge and also to entirely close the same during winter and thereby obviate the necessity of plugging the drain of a refrigerator car.

With these and other objects in view the invention consists in the construction and novel combination and arrangement of parts hereinafter fully described, illustrated in the accompanying drawings and pointed out in the claims hereto appended, it being understood that various changes in the

form, proportion and minor details of construction may be resorted to without departing from the spirit or sacrificing any of the advantages of the invention.

In the drawings Figure 1 is a side elevation of a refrigerator car drain and air excluder constructed in accordance with this invention, Fig. 2 is an end elevation of the same, Fig. 3 is a central longitudinal sectional view of the refrigerator car drain and air excluder, Fig. 4 is a horizontal sectional view taken substantially on the line 4-4 of Fig. 3, Fig. 5 is a detail sectional view illustrating the construction of the catch for locking the trough or chute of the drain in its adjustment.

Like numerals of reference designate corresponding parts in the several figures of the drawings.

In the accompanying drawings, 1 designates a drain pipe of an ice bunker or compartment of a refrigerator car, not shown, provided with a flared upper portion 2 connected to and preferably formed integral with a horizontal plate 3. The drain pipe 1 and the plate 2 may be constructed of malleable metal or any other suitable material which is also true of the other parts of the device as any suitable material may be employed in the construction thereof. The top plate 3 is provided with bolt openings for the reception of bolts 4 arranged vertically and also passing through slots 5 of stems or attaching portions 6 of clamping members which have approximately semi-circular portions 7 forming bearings and adapted to support a lower tubular section 8 composed of an upper cylindrical portion 9, a lower rectangular or square portion 10 and a horizontal plate or flange 11 arranged upon and supported by the semi-circular bearing portions 7. The clamping members are angularly bent at 12 to form shoulders for engaging the edge of the plate or flange which is preferably circular to enable the lower tubular section 10 and the trough or chute 14 carried by the tubular section to rotate whereby the trough or chute is prevented from being brushed off should it come in contact with an object when turned transversely of the car. The outer portions of the shank 6 are provided with perforations 15 for the reception of screws or other suitable fastening

devices for securing the clamping members after the same have been adjusted into proper engagement with the plate or flange 10 of the lower tubular section.

5 The drain pipe 1 which is vertical depends within the upper cylindrical portion of the lower section and extends below the upper end of the same and is arranged in spaced relation with the said cylindrical portion 9 as clearly shown in Fig. 3 of the drawings.

10 The lower rectangular portion 10 of the lower section has straight parallel sides and it is tapered to form lower inclined edges 16 at the said sides to coact with the bottom 17 of the trough or chute which is arranged at 15 an inclination and which is movable to adjust the bottom 17 toward and from the inclined edges 16 to vary the size of the openings of the lower section of the drain and 20 also to close the drain when desired to obviate the necessity of plugging the same. The trough 14 which is composed of sides and the bottom 17 is hinged at its upper end at 18 to the lower rectangular portion of the 25 tubular section 8 and it is secured in its adjustment by means of a catch consisting of a spring actuated bolt 19 located at one side of the trough and adapted to engage any one of an arcuate series of perforations 20 formed 30 in one of the sides of the rectangular portion of the lower tubular section. The bolt 19 is provided at its outer end with a head 21 and it is urged inwardly by a coiled spring 22 arranged within a tubular casing 23 35 which has an attaching plate or flange 24 secured to the adjacent side of the trough 14. The tubular casing or housing is provided with an outer end wall 25 through which the bolt passes and the spring is interposed between the end wall and a pin 26 or other suitable stop.

40 The trough is provided below the rectangular portion 10 with a curved partition 27 extending from the bottom of the trough 45 to a point above the outlet of the lower tubular member 8 and terminating short of the upper edges of the sides and presenting a concaved upper face. The curved partition 27 which extends transversely of the 50 trough forms an upper trap receptacle for holding the water resulting from the melting of the ice to submerge the lower end of the tubular section 8. Also the drain pipe by extending below the upper edge of the 55 cylindrical portion 9 enables the water to drop clear of the sides of the tubular member 8 and prevents accumulation of ice in cold weather which stops the drain pipe now in use. The sides 14 of the chute are 60 in sufficient contact with the side of the section 10, to prevent air or gases from passing laterally through the opening formed between the bottom 16 of the section 10 and the chute 17. Any cinders or similar accumulation 65 collecting in the trap will be

jarred or jolted out of the same by the motion of the car. The transverse partition may be omitted if desired. Also the open trough is adapted to afford ready access to the trap and will enable any accumulation 70 of ice in cold weather to be readily removed.

What is claimed is:—

1. A drain for refrigerator cars including a drain pipe, a lower discharge pipe, a chute carried by the lower end of the discharge pipe and forming a partial closure for the same, said chute being also provided with a transverse partition arranged to form a trap for submerging the lower end 75 of the discharge chute.

2. A drain for refrigerator cars including a discharge pipe having a substantially rectangular portion, an inclined chute receiving the rectangular portion of the discharge pipe and hinged to the same whereby the chute is movable toward and from the discharge pipe to vary the size of the outlet and means for securing the discharge chute in its adjustment.

3. A drain for refrigerator cars including a discharge pipe having a substantially rectangular portion, an inclined chute receiving the rectangular portion of the discharge pipe and hinged to the same whereby the chute is movable toward and from the discharge pipe to vary the size of the outlet, a transverse partition carried by the chute and located beyond the discharge pipe to form a trap and means for securing the chute in its adjustment.

4. A drain for refrigerator cars including a discharge pipe, means for mounting the same for rotary movement, and a chute carried by the discharge pipe and forming a partial closure for the same and adapted to 105 be turned in different directions through the rotary movement of the discharge pipe.

5. A drain for refrigerator cars including a discharge pipe having a tapered lower end forming inclined edges and a chute 110 hinged to the discharge pipe and having a bottom arranged to move toward and from the inclined edges to form a closure for the discharge pipe and also to vary the size of the outlet.

6. A drain for refrigerator cars including a discharge pipe, an annular flange thereon, a chute carried by the discharge pipe and located below the flange and supporting members provided with curved 120 bearing portions receiving the flange of the discharge pipe.

7. A drain for refrigerator cars including a discharge pipe composed of a cylindrical upper portion and a rectangular lower portion and provided with a horizontal flange and clamping members composed of shanks and curved bearing and supporting portions located at opposite sides of the discharge pipe and receiving the said flange.

8. A drain for refrigerator cars including a drain pipe provided at the top with a plate, clamping members having shanks provided with slots, said clamping members being also provided with curved bearing portions, fastening devices arranged in the said slots and connecting the clamping members with the said plate and a discharge

pipe having a flange supported by the clamping members.

In testimony whereof I affix my signature in presence of two witnesses.
